MANIFOLDING

Carl W. Brenn, Montclair, N. J., assignor to Auto-graphic Register Company, Hoboken, N. J., a corporation of New Jersey

Application December 3, 1925, Serial No. 72,921

4 Claims. (Cl. 282—12)

This invention relates to manifolding, and more particularly to worksheets used in making original and duplicate copies.

Heretofore, it has been the practice to supply and use worksheets of considerable length comprising, in succession, a relatively large number of printed forms or sheet lengths superposed upon one another so that in use, by the interpositioning of transfer material such as carbon paper, between the superposed worksheets, manifold copies could be made on the form or sheet lengths one after another continuously without necessitating the separate handling of the individual forms or sheet lengths.

In order that the superposed worksheets might be held together in predetermined relation to each other, for instance, in alignment and registration, it was the practice to make the superposed worksheet from a single web of paper and fold the web with one strip of forms upon the other in the manner of folding a fan and producing what is termed fan-fold stationery.

It has also been proposed to paste or otherwise fasten separate continuous strips of forms together, so that at one side edge, the pile of strips would be held together. Such stationery will be termed book-fold stationery.

In both of the fan-fold and the book-fold type of stationery, the strips, because of the fact that they are only attached to each other at one side edge, have considerable freedom of relative movement, and, therefore, permit a disalignment or lack of registration of one form relative to its companion superposed form. This condition existed because, to interpose carbon sheets between the superposed strips and shift them from form to form, it was necessary to allow one side edge between each two forms to be open.

It was also proposed to paste or secure the forms together at both side edges, but this was not done for the purposes of maintaining registration. But even in this type of stationery, the separate strips were split or separated as they approach the position at which the carbon sheets were interposed between them. Hence, at the very point where registration and alinement was most essential, i. e. at the writing point the strips were free to shift sidewise relatively, and this caused disalignment and lack of registration.

The present invention overcomes these disadvantages by providing a pack of stationery comprising superposed worksheets and interposed carbon sheets with the worksheets se-

cured at both side edges so as to hold them in registration and alinement and to confine, or make captive in the pile, the interposed carbon strips.

According to the present invention, this is accomplished by securing both side edges of the worksheets together after superimposing them and interposing the carbon sheets, with an adhesive preferably composed of a rubber composition or gum as, for instance, as described in the patent to Brick, No. 1,314,782, June 1, 1920.

It is customary, in making continuous stationery both of the fan-fold and book-fold type, to transversely fold the pile of worksheets in zigzag form so that a compact pack of stationery will be provided. To prevent the zigzag folded pack of stationery from falling over, it is usually placed in a box or other container.

The present invention avoids the necessity of providing a container or support for the pack of zigzag folded stationery by uniting, preferably by an adhesive, all of the side edges of the worksheets in zigzag folded form so as to provide a single unitary pack. This adhesive is preferably such that will part or separate when the superposed layers of the pack are pulled from the body of the pack as the stationery is being consumed.

The provision of adhesive between the superposed strips to hold them together and to hold the carbon sheets captive between them and the provision of the adhesive for holding the zigzag pack of worksheets together may be accomplished by separate operations. But, in practicing the present invention, it has been found that both these provisions may be made at a single operation.

Accordingly, the present invention also comprises a method of making a pack of stationery which consists in collating the workstrips and carbon strips, folding them zigzag so as to provide a pile or pack, pressing the pack so as to bring the side edges of the worksheet in a zigzag form close together, and then applying a layer of adhesive material upon the side edges of the pack.

In cases where it is important to have each form and its companion form in absolute alinement, the worksheets are provided with alining apertures which may be received upon suitable pins after the strips are collated and before the side edges of the worksheets are closely brought together. These pins correct the inaccuracies of registration which are produced at the folds of the pile.

Other features and advantages will hereinafter appear.

In the accompanying drawing, which illustrates the present invention and the apparatus 5 which may be used for assisting in carrying out the methods herein disclosed—

Figure 1 is a perspective view of the pad of worksheets provided by the present invention.

Fig. 2 is an elevation showing apparatus for 10 bringing the side edges of the pack together, and also showing means for applying the adhesive to the side edges.

Fig. 3 is an exaggerated sectional view, showing 15 several superposed worksheets in their superposed pack relation.

Fig. 4 is a view of the modification.

In the accompanying drawing, the pack of stationery is shown as comprising a top-sheet 1 and an under-sheet 2, both of which may have 20 printed lines 3 and spaces 4 which are adapted to receive indicia relating to an order, sale, or the like. Between the top-sheet 1 and the under-sheet 2, there is interposed a carbon or transfer sheet 5 so that original writing produced upon the sheet 1 will be transferred to the sheet 2 by means of the carbon sheet 5.

Preferably, a pile is formed of the superposed worksheets 1 and 2 and the interposed carbon sheet 5, each of which consists of a strip of 30 definite length folded along lines 6 which is at the point where one form joins with the next.

In order to hold the sheets in accurate alignment and registration with each other, the present invention provides, along both side edges 35 of sheets, a sufficient mass of adhesive material 7 to hold the sheets firmly together and to confine between them the carbon strip 5. This adhesive material may be applied to the edges of the superposed sheets 1 and 2 before they are 40 zigzag folded, but, in order to economically do this and at the same time connect together the layers of the zigzag folded pile, the present invention provides the following method:

First, the worksheets 1 and 2 with the interposed carbon strip 5 are collated. Then, the superposed carbon and worksheets are folded transversely in zigzag form preferably along the lines 6, which are usually perforated and which facilitate the folding operation. Then 50 the zigzag folded pack is pressed together preferably in a press 8 so as to bring the side edges of the worksheets into close contact with each other. Finally, the side edges of the pack are provided with a coating of adhesive material 7, 55 for instance, by a brush 9 while the pack is held compressed in the press 8. The adhesive is allowed to dry and the pack is then removed from the press, ready for use.

In using the pack of stationery provided by 60 the present invention, the uppermost layer of the zigzag folded pack comprising the top-sheet 1 and the under-sheet 2 and the confined carbon sheet 5 is removed from the pack. By simply pulling this end of the pack from the remainder, each set of forms is stripped from the other sets still remaining en bloc and as the strips are drawn from the pack they carry with them a part of the adhesive material which is upon their particular side edges. The 65 result is that the top and bottom strips of the set of forms removed from the pack are still held together by the adhesive along their side edges. In this condition, the end of the strip may be placed in a typewriting machine or 70 manifolding register or other writing machine 75

to receive impressions upon the top sheets which are transferred to the under-sheet 2 through the confined carbon strip 5.

When the adhesive material is a rubber composition or gum, as is preferable, it will be flexible and permit the group or pile of strips to be fed around a typewriter cylinder or other circular object without the adhesive cracking or breaking.

After the sheets have been written, they are 10 easily separated by pulling them apart, the adhesive material uniting them again splitting so that each sheet carries on its side edge only a very small amount of adhesive material.

The worksheets provided by this invention 15 comprising superposed workstrips with interposed carbon sheets can be used in cases where it would be impractical or undesirable to provide, upon the back of one of the worksheets, a coating of carbon materials to be used to 20 transfer impressions to the under-sheet. With the pack of the present invention, the backs of both sheets may be clean, i. e. unprinted, or may be provided with printing, if desired.

It has been found that in zigzag folding the 25 continuous worksheets, there is always a slight disalignment between successive forms due to the fact that the sheets are slightly off-set at the points of folding.

To avoid this off-set in cases where it is desired to have the strips in absolute alignment, the present invention provides means for alining and registering the strips. This means comprises apertures or perforations 10 provided in the body of the forms. The perforated strips 1 35 and 2 and the carbon strip 5 are adapted to be placed upon collating or alining pins 11 carried by a suitable base 12 before the zigzag folded pack is compressed to permit adhesive material to be applied to its side edges. 40

If desired, the pack may consist of a single sheet of paper, as shown in Fig. 4, in which the strip 13 is folded longitudinally upon itself. In this case, the carbon strip 5 is placed between the folds of the sheet, and after the strip is zigzag folded, a coating of adhesive material 7 is applied only to that side of the pile of sheets which comprise the unfolded edges of the strip. The adhesive coating may be applied, however, to the other side edges of the pack, if desired. 50

Variations and modifications may be made in accordance with this invention, and portions of the improvements may be used without others.

Having described the invention, what is claimed as new and for which it is desired to obtain Letters Patent, is:

1. A manifolding pile comprising a plurality of physically separate, continuous worksheet strips; a continuous carbon strip between each two worksheet strips running with said worksheets in interleaved relation; and means located along both side edges of the pile of strips for holding the worksheet strips of the pile together with the carbon strip or strips and in registration preparatory to, during, and subsequent to the operation of writing upon said worksheet strips. 60

2. A manifolding pile comprising a plurality of continuous worksheet strips and a continuous carbon strip interposed between two adjacent 70 worksheet strips, the carbon strip being shaped to provide zones of face-to-face direct contact of adjacent worksheet strips with each other at both lateral margins of the pile; and means located in each of said zones of direct contact for 75

securing adjacent worksheet strips together, said means being adapted to restrict lateral shifting movements of the carbon strip in the pile.

- 5 3. A manifolding pile comprising a plurality of continuous worksheet strips and a continuous carbon strip interposed between two adjacent worksheet strips, the carbon strip being shaped to provide zones of face-to-face direct contact 10 of adjacent worksheet strips with each other at at least one lateral margin of the pile; and means located in said zones of direct contact for se-

curing adjacent worksheet strips together, said means being adapted to restrict lateral shifting movements of the carbon strip in the pile.

4. A manifolding pack comprising a pile of continuous record and carbon strips interleaved 5 with each other, the pile being folded zigzag at uniform intervals to form a pack; and a coating of adhesive material applied to both edges of the pile of folded strips to hold the strips of the pile together and to hold the layers of the zig- 10 zag folded pack together until ready for use.
